CLAIM

The ornamental design for a display screen or portion thereof with animated graphical user interface, as shown and described.

DESCRIPTION

FIG. 1 is a front view showing a first image in a sequence of a display screen or portion thereof with animated graphical user interface, showing our new design; FIG. 2 is a front view of a second image thereof; FIG. 3 is a front view of a third image thereof; FIG. 4 is a front view of a fourth image thereof; FIG. 5 is a front view of a fifth image thereof; FIG. 6 is a front view of a sixth image thereof; and, FIG. 7 is a front view of a seventh image thereof.

The appearance of the animated graphical user interface sequentially transitions between the images shown in FIGS. 1-7. The process or period in which an image transitions to another image forms no part of the claimed design.

The dot-dash broken lines showing a display screen or portion thereof is for the purpose of illustrating portions of the article and form no part of the claimed design.
